UNITED STATES PATENT OFFICE.

HARRY S. HUMES, OF VENICE, CALIFORNIA.

SUN-GLARE EYESHIELD.

Application filed April 24, 1924. Serial No. 708,661.

To all whom it may concern:

Be it known that I, HARRY S. HUMES, a citizen of the United States, residing at Venice, in the county of Los Angeles and State of California, have invented new and useful Improvements in Sun-Glare Eyeshields, of which the following is a specification.

This invention relates to eye shields.

10 An object is to make an eye shield that is readily adjustable to heads of different sizes, and which is readily adjustable to different conditions.

15 Another object is to make a main frame, and a shield adjustably mounted on the frame and adapted to swing downwardly to engage the nose or face of a wearer.

20 Other objects and advantages will appear from the drawings and specification.

25 The drawings illustrate the construction and use of the invention.

Figure 1 is a plan of an eye shield embodying the principles of my invention.

Fig. 2 is a fragmentary side elevation of 25 the eye shield in position for use.

Fig. 3 is a fragmentary cross section on the line 3—3 of Fig. 1, and looking in the direction indicated by the arrows.

30 Fig. 4 is a plan of a modified form of the shield plate.

The details of the eye shield shown in the drawings are as follows:

The principal frame 1 is formed of a substantial wire and has straight aligned shaft 35 portions 2 and 3, arm portions 4 and 5 extending downwardly at right angles to the inner ends of the shaft portions 2 and 3, the nose bridge portion 6 connecting the lower ends of the arm portions 4 and 5 by return

40 bends 7 and 8, and the bow hinge fittings 9 and 10 upon the outer ends of the shaft portions 2 and 3. The supporting bows 11 and 12 are connected to the fittings 9 and 10 in the usual way. The adjustable support

45 13 is mounted upon the shaft portion 2 and the adjustable support 14 is mounted upon the shaft portion 3. The adjustable support 13 is formed of a substantial wire and consists of the straight outer brace bar 15

50 having its inner end bent to form a bearing 16 encircling and slidably and rotatably mounted upon the shaft portion 2, a return bend 17 at the opposite end of the bar 15 from the bearing 16, an outwardly bowed bearing bar 18 extending from the return bend 17 and having a bearing 19 encircling

and slidably and rotatably mounted upon the shaft portion 2. The adjustable support thus constructed is adapted to be moved inwardly or outwardly upon the shaft portion 2 to fit heads of different sizes and so that the bar 18 will engage the side of a head above and back of the eye.

In a like manner, the adjustable support 14 consists of a brace bar 20, a bearing 21, a return bend 22, a bearing bar 23, and a bearing 24 adjustably mounted upon the shaft portion 3.

The adjustable supports 13 and 14 will turn upwardly or downwardly, and may be moved inwardly or outwardly to provide a wide range of adjustment for different conditions and different heads.

The secondary shaft 25 is mounted parallel with the shaft portions 2 and 3. Links 26 and 27 are formed of strips of flat metal, as shown in Fig. 3, one end of the strip being bent tightly around the shaft 25 and the other end of the strip being bent around the shaft portion 3 to form a hinge connection. The shaft 25 is formed of a substantial wire, and arms 28 and 29 extend from the ends of the shaft forwardly or downwardly substantially at right angles to the shaft and the arms 28 and 29 may be, and preferably are, bowed outwardly between their ends. Bearing blocks 30 and 31 are secured to the arms 28 and 29 and to the outer ends of the shaft 25 by soldering, clamping, or the like, said bearing blocks 30 being formed of flat metal and the free ends of the flat metal are bent around the shaft portions 2 and 3 so as to hingedly connect the arms 28 and 29 to the shaft portions 2 and 3. A plate 32 of suitable material such as celluloid fits in the frame formed by the shaft 25 and the arms 28 and 29, and is held by clips 33, 34, 35 and 36. Each clip 33 to 36 consists of a piece of flat soft metal bent around the frame member 30 and extending under the plate 32 and upwardly through the plate and bent outwardly.

The plate 32 is preferably semi-transparent and may be colored or tinted, preferably green, as required to protect the eyes of a wearer from the glare of sunlight or artificial light, such as electric lamps, welding and cutting torches, and the like.

Under ordinary conditions of weather, the parts may be adjusted so that the plate 32 extends forwardly and downwardly rela-

tive to the eyes 37 as shown in Fig. 2, and when the conditions are bad as when wind and dirt is attacking the eyes, the plate 32 may be turned downwardly and engage the nose 38 as indicated by the dotted line 39 so as to protect the eyes from flying material such as the sparks from an emery grinder or a cutting and welding torch or a storm.

- 10 Thus I have produced an eye shield having a main frame, including a nose bridge, bearing members adjustably mounted on the main frame to engage the sides of a head, and a shield adjustably mounted on the 15 main frame and adapted to swing downwardly to engage the face of a wearer.

In the modification of the shield plate shown in Fig. 4, the plate 40 has an extension portion 41 extending backwardly from 20 the dotted line 42 and having a concaved rear edge 43 to fit against the forehead, the portion 41 extending above the adjustable supports 13 and 14 so as to better shield the eyes.

25 The drawings are more or less diagrammatic and suggestive, and it is to be understood that various changes may be made without departing from the spirit of the invention as claimed.

20 I claim:

1. A sun glare eye shield comprising a principal frame formed of a substantial wire

having straight alined shaft portions, a nose bridge formed between the inner ends of the shaft portions, supporting bows hinged to the outer ends of the shaft portions, adjustable supports mounted upon the shaft portions and adapted to be moved inwardly or outwardly and turned upwardly or downwardly and adapted to engage the side of a head above and back of the eyes, a secondary shaft connected to the shaft portions by links, arms extending forwardly from the ends of the secondary shaft, and a plate connected to the secondary shaft and to the arms and adapted to be swung from a vertical position against a nose forwardly and upwardly.

2. A sun glare eye shield comprising a principal frame formed of a substantial wire 50 having straight alined shaft portions, a nose bridge formed between the inner ends of the shaft portions, supporting bows hinged to the outer ends of the shaft portions, adjustable supports mounted upon the shaft portions and adapted to be moved inwardly or outwardly and turned upwardly or downwardly and adapted to engage the side of a head above and back of the eyes, 55 and a plate hingedly connected to the shaft portions.

In testimony whereof I have signed my name to this specification.

HARRY S. HUMES.
